(57) **CLAIM**

The ornamental design for a USB flash drive pen, as illustrated.

DESCRIPTION

FIG. 1 illustrates a front perspective view of a USB flash drive pen with the USB flash drive in an inserted position.

FIG. 2 illustrates a front perspective view of the USB flash drive pen with the USB flash drive in an extracted position.

FIG. 3 illustrates a side perspective view (from the rear) of the USB flash drive pen with the USB flash drive in an extracted position.

FIG. 4 illustrates a side perspective view (from the rear) of the USB flash drive pen with the USB flash drive in an inserted position.

FIG. 5 illustrates a top perspective view of the USB flash drive pen with the USB flash drive in an inserted position.

FIG. 6 illustrates a top perspective view of the USB flash drive pen with the USB flash drive in an extracted position.

FIG. 7 illustrates a rear perspective view of the USB flash drive pen with the USB flash drive in an inserted position; and,

FIG. 8 illustrates a rear perspective view of the USB flash drive pen with the USB flash drive in an extracted position.
